TIRE RACK

Ben W. Harley, Robert C. Shape, and Norris H. Mealy,
all of Warren, Ohio, assignors to The Warren Steel
Specialties Corporation, a corporation of Ohio

Filed July 22, 1959, Ser. No. 56,885

Term of patent 14 years

(Cl. D80—10)

Figure 1 in a side elevational view of a tire rack showing our new design;

Figure 2 is a front elevational view thereof;

Figure 3 is a front perspective view taken from the top thereof; and

Figure 4 is an enlarged perspective view of one of the tire supports thereof.

The dotted line showing of tires in Figure 1 is for purposes of illustration only.

The dominant features of our design reside in the portions shown in full lines in the drawing.

We claim:

The ornamental design for a tire rack, substantially as shown and described.
